FILLING REPLENISHING LOOM

Carl D. Brown, Hopedale, Mass., assignor to
Draper Corporation, Hopedale, Mass., a cor-
poration of Maine

Application March 16, 1932. Serial No. 599,226

6 Claims. (Cl. 133—231)

This invention relates to filling replenishing looms of the type including a shuttle feeler for revoking the call for filling replenishment when the shuttle is not boxed properly.

5 It is usual practice in such looms to operate a series of mechanisms from a single cam on the cam shaft. That is, the single cam operates a so-called weft hammer which, in turn furnishes the motive power for initiating the stopping of 10 the loom under control of the filling fork, and for initiating the operation of the replenishing mechanism under control of the filling feeler or filling fork, as the case may be. Call for replenishment is initiated by moving a shuttle feeler to rearward 15 operative position, movement of the shuttle feeler also serving to position the parts of the replenishing mechanism proper for operation by the lay.

This attempt to operate a multiplicity of mechanisms from a single cam, while desirable for 20 many obvious reasons, makes it difficult to obtain the proper timing of the various parts. The cam ordinarily used imparts a sequence of movements to the weft hammer that times the operation of the various mechanisms satisfactorily except 25 that the shuttle feeler is operated too early, it frequently happening that the shuttle feeler is moved rearwardly into the path of the shuttle before the latter has completed its flight, with various disastrous results.

30 One way to overcome this difficulty, without disturbing the other parts involved, is to delay the time of movement of the shuttle feeler until the shuttle has had ample time in which to complete its flight. Devices for accomplishing this result are disclosed in the Rhoades Patent 1,328,452 granted January 20, 1920. While the Rhoades device operates satisfactorily it is subject to a number of disadvantages, not the least of which are that the positioning of the parts on 35 the top of the breast beam is inconvenient and undesirable, and that the particular devices are expensive to make and difficult of accurate adjustment.

40 It is, accordingly, an object of my invention to provide an improved shuttle feeler delaying device that is simple in construction and reliable in operation. To this end, the invention contemplates the provision of delaying parts carried by 45 the shuttle feeler itself and the shuttle feeler supporting bracket, whereby the entire shuttle feeler mechanism is self contained and may be assembled in the loom as a unit, thus dispensing with the necessity for correlating and fitting vari- 50 ous independently mounted parts.

It is usual practice to provide filling replenishing looms with a thread cutting and holding device, for severing the filling extending from the selvage to the shuttle, just before replenishment; such device operating in the region of the 60 shuttle and serving also to hold the end leading to the selvage until it is trimmed off by the usual selvage trimming devices, such as the temple thread cutter. In the construction heretofore employed, regardless of whether the thread cutting and holding device was mounted on the shuttle feeler or merely operated thereby, the interconnection between the shuttle feeler and the replenishing mechanism results in the thread cutter having the following movements: first, 65 rearwardly to operative position, then a quick snap forwardly and rearwardly while the replenishing operation takes place, and then a final forward movement to inoperative position. The 70 quick snap forwardly and rearwardly is undesirable as it serves to place an undue strain on the filling extending from the thread cutter to the selvage, and oftentimes either breaks the filling or causes it to pull out from between the jaws of the cutter, whereupon the end will not be 75 brought within range of the selvage trimmer and may, indeed, be whipped into the shed and then 80 woven into the cloth.

It is, accordingly, a further object of my invention to provide means for holding the thread cutter in its forward retracted position after it has been moved there by the connections with the replenishing mechanism, thus preventing it from snapping rearwardly before being finally moved 85 to forward inoperative position. This object 90 may be conveniently accomplished by the proper arrangement of the shuttle feeler delaying parts.

Further objects of my invention will, in part, be hereinafter more specifically pointed out, or 95 will become obvious as the description proceeds.

Referring to the drawings, in which:

Fig. 1 is a perspective view of the right front corner of a loom embodying my invention:

Fig. 2 is an elevation of the shuttle feeler and its operating and delaying devices, taken from 100 the right of Fig. 1, certain parts being broken away or omitted to more clearly show my invention, and

Fig. 3 is a view similar to Fig. 2, but showing 105 the shuttle feeler in its forward inoperative position.

The loom illustrated in the drawings, to which my invention has been applied, may include the usual reciprocating lay 1 carrying a reed 2, the upper surface of the lay, and front surface of 110

the reed serving to guide a shuttle 3 which is picked from side to side of the loom, along the lay, and is received at opposite ends of the lay in shuttle boxes, only the right hand box, 4, being illustrated.

The loom may also include a suitable replenishing mechanism, herein shown as a hopper 5 for holding a reserve supply of full bobbins and a transfer hammer 6 operated by a bunter 7 on the lay when dog 8 is properly positioned to be struck thereby. The positioning of dog 8 for replenishment is accomplished through the medium of shaft 9 and connections hereinafter described, the shaft being operated from the usual weft hammer under control of the filling feeler or filling fork, as the case may be.

The foregoing, and other elements of the loom not illustrated, may be of any suitable usual construction and, since they form no part of the present invention, they do not require detailed description. Suffice it to say that, upon call for replenishment, shaft 9 is rotated counter clockwise from the position shown in Fig. 3 and maintained in this rotated position until after the replenishing operation is completed. Since this rotation starts shortly after the time the lay starts back with the shuttle in the left hand box and is completed before the lay starts forward again (the shuttle having been picked in the meantime) the shuttle feeler will be moved to rearward operative position before the shuttle has completed its flight. Should the shuttle be a little slow in its movement it will be carried forward by the lay and reed and may strike the shuttle feeler. It is with the prevention of this interference between the shuttle feeler and shuttle that one aspect of my invention is concerned.

Shaft 9 carries an arm 10 to which a forked lever 11 is pivoted as at 12. One arm of the lever 11 is engaged by a coiled tension spring 13 and the other arm is forked as at 14 to engage a pin 15 extending laterally from the arm 16 of the shuttle feeler. Also extending laterally from the shuttle feeler, but in the opposite direction from pin 15, is a pin 17 carrying a cam 18 for controlling a pin 19 projecting from a downwardly extending portion of dog 8. It is noted particularly that arm 10, lever 11, spring 13, etc., serve to yieldingly move the shuttle feeler to operative position.

The foregoing shuttle feeler and replenishing parts may be, and are shown as, identical with those disclosed in the patent to E. C. Nichols, No. 1,820,821, granted August 25, 1931, although other arrangements may be employed if desired.

The shuttle feeler is, as shown, pivoted on a bolt 20 projecting from a bracket 21 adjustably secured as by bolts or screws 22 to the loom frame. The bracket 21 carries a fixed stop 23, preferably formed as an integral extension on the bracket. A movable latch member, herein shown as a lever 24, is pivoted at one end on a stud 25 fixed in an arm 26 formed integral with the shuttle feeler. The other end of the member 24 is provided with a lug 27 having a face adapted to engage stop 23 and hold the shuttle feeler in an intermediate position against the action of the yielding moving means for the shuttle feeler. A spring 28, having one end fixed to pin 25 and the other end engaging the top of lug 27, serves to bias the member 24 to the position where lug 27 can engage stop 23 when the shuttle feeler is moved rearwardly.

A bell crank lever, pivoted at 29 to the arm 26 of the shuttle feeler, has one arm 30 operatively

related to the member 24 and its other arm 31 extending vertically in the path of a bunter 32 carried by the lay, operation of the bell crank lever by the bunter serving to lift member 24 and thereby disengage it from the stop 23 as the lay approaches the end of its stroke. A spring 33 having one end secured to the shuttle feeler and its other end secured to the bell crank lever serves to return the latter to normal position after its release from contact with the bunter.

The accompanying drawings illustrate, fragmentarily, a thread cutter comprised of opposed cutting and thread holding jaws 34, 35 mounted on the shuttle feeler. The thread cutter may be of any of a member of constructions now well known and therefore need not be illustrated or described in minute detail. Such prior art thread cutters operate in the region of the shuttle and are either mounted directly on the shuttle feeler or supported by the battery and moved by the shuttle feeler. I have illustrated the former type, merely as a matter of convenience.

The operation of the device is as follows: Assume that after a call for replenishment, the shuttle is just being picked toward the replenishing side of the loom, the lay is making its backward stroke, and shaft 9 is turning to raise arm 10. When arm 10 has moved the shuttle feeler rearwardly approximately half of its total movement lug 27 will engage stop 23 and hold the shuttle feeler in this intermediate position. Continued movement of the arm will result in lever 11 pivoting about pin 15 as a fulcrum, with a resultant stressing of spring 13.

During the time required for the lay to complete its rearward stroke and move forward again, on the replenishing beat-up, to the position near the end of its stroke, Fig. 2, the shuttle will have completed its flight and boxed on the replenishing side of the loom. Then, as the lay approaches the forward end of the stroke, bunter 32 will strike arm 31 of the bell crank lever, causing the other arm 30 to lift member 24, thereby disengaging the latter from stop 23 and allowing spring 13 to quickly move the shuttle feeler the rest of the way to its rearward operative position. The thread cutter then operates to sever and clamp the filling extending from the shuttle to the selvage.

If the call for replenishment is not revoked by the shuttle feeler the transfer hammer 6 will be operated by bunter 7 striking dog 8, while the lay is at front center. Movement of the transfer hammer operates, through dog 8, pin 19, cam 18 and pin 17, to retract the shuttle feeler forwardly. Then, when the lay goes back and the transfer hammer rises, spring 13 tends to snap the shuttle feeler and thread cutter rearwardly again. This, however, is prevented by the re-engagement of lug 27 with stop 23, bunter 32 having moved far enough back to release arm 31 of the bell crank lever and permit spring 33 to return the latter to normal position. Then, after the lay is well back, shaft 9 is rotated to lower arm 10 and thus return the parts to their normal position.

It is apparent from the foregoing that I have provided not only an improved shuttle feeler delaying device but also means for preventing a forward and rearward snap of the thread cutter at the time of transfer. The particular embodiment herein disclosed is, of course, merely illustrative of one way in which my invention may be practiced, as numerous variations and modifications may be resorted to without departing

from the spirit of the invention as defined in the appended claims.

Having fully disclosed the preferred embodiment of my invention, I claim:

5. In a filling replenishing loom, a shuttle 80
feeler, means for yieldingly moving the shuttle
feeler to operative position upon call for re-
plenishment of filling, a fixed stop, a movable
member carried by the shuttle feeler for engag-
10 the said stop and thereby holding the shuttle
feeler in an intermediate position, and a lever,
likewise carried by the shuttle feeler, for disen-
gaging the said member from the said stop;
15 whereby the movement of the shuttle feeler to
operative position is momentarily delayed against
the action of said yielding means.
2. In a filling replenishing loom, the combina- 85
tion of the lay, a shuttle feeler, means for yield-
ingly moving the shuttle feeler from frontward
20 to rearward operative position, upon call for re-
plenishment of the filling, a fixed stop, a movable
member carried by the shuttle feeler for engag-
ing the said stop and thereby holding the shuttle
feeler in an intermediate position against the
25 action of the said yielding means, a lever car-
ried by the shuttle feeler for disengaging the said
member from the said stop, and means operat-
ing said lever as the lay approaches the end of
its stroke on the replenishing beat-up.
3. In a filling replenishing loom, the combina- 90
tion of the lay, a shuttle feeler, means for yield-
ingly moving the shuttle feeler from frontward
25 to rearward operative position, upon call for re-
plenishment of the filling, a fixed stop, a lever
pivoted on the shuttle feeler and spring-biased
40 to a position where it can engage the said stop
to thereby hold the shuttle feeler in an inter-
mediate position against the action of said yield-
ing means, a bell crank lever pivoted on the
45 shuttle feeler and having one arm thereof in
operative relation to the first mentioned lever,
and means for causing said bell crank lever to
disengage the said first named lever from the
50 said stop as the lay approaches the end of its
stroke on the replenishing beat-up.
4. A shuttle feeler delaying device including, in
combination with the shuttle feeler movable to
and from operative position and a bracket for
supporting the same, a fixed stop carried by the
said bracket, a movable member carried by the
55 shuttle feeler for engaging the said stop and
thereby holding the shuttle feeler in an inter-
mediate position, a bell crank lever pivoted ad-
jacent the said member and having one arm in
operative relation thereto, and means engaging
60 the other arm of said lever for disengaging the
said member from said stop.
5. A shuttle feeler delaying device including, in
combination with the shuttle feeler movable to
and from operative position and a bracket for
supporting the same, a fixed stop mounted inde-
pendent of the shuttle feeler, a movable mem- 95
ber associated with the shuttle feeler for engag-
ing the said stop and thereby holding the shuttle
feeler in an intermediate position, a lever piv-
oted to the shuttle feeler and having one arm
in operative relation to said member, and means
for operating the other arm of said lever to there-
by disengage the said member from said stop.
6. In a filling replenishing loom, the combina- 100
tion of the lay, a thread cutter for cutting the
filling in the region of the shuttle, means for
yieldingly moving the thread cutter to rearward
operative position upon call for replenishment
105 of the filling, said means tending to hold the
thread cutter in operative position throughout
the replenishing operation, filling replenishing
mechanism, connections between the thread cut-
ter and the replenishing mechanism for posi-
110 tioning the latter for operation by the lay when
the former is moved to operative position, said
connections serving to retract the thread cutter
from operative position against the action of the
said yielding means when the replenishing oper-
ation takes place, and means including a latch
115 for latching the thread cutter in such retracted
position.
